UNITED STATES PATENT OFFICE

1,996,030

ELECTRIC SWITCH

Rudolf Popp, Valparaiso, Ind., assignor to McGill Manufacturing Company, Valparaiso, Ind., a corporation of Indiana

Application November 10, 1933, Serial No. 697,422

11 Claims. (Cl. 200—64)

My invention relates to electrical switches. It relates more in particular to a relatively small size switch adapted particularly for controlling light circuits as, for example, in homes and offices.

The principal object of the invention is the provision of an improved switch.

Another object is the provision of a switch having a small number of simple parts and capable of easy assembly.

Another object is the provision of an inexpensive switch which will have a long life.

Another object is the provision of improved means for connecting conductors to the switch.

Another object is the provision of an improved switch combination so arranged that the possibility of short circuiting any portions thereof is substantially entirely obviated.

Other specific objects and the details of the invention will appear from the following description taken with the accompanying drawing, wherein

Fig. 1 is a perspective view of the improved switch of my invention;

Fig. 2 is an elevational view showing a feature which permits easy attachment of conductors;

Fig. 3 is an elevational view with the cover removed, the view looking along the line 3—3 of Fig. 5;

Fig. 4 is a longitudinal staggered sectional view taken along the line 4—4 of Fig. 5;

Fig. 5 is a staggered sectional view taken in general in a longitudinal direction along the line 5—5 of Fig. 3;

Fig. 6 is a transverse sectional view partly in elevation taken along the line 6—6 of Fig. 4;

Fig. 7 is a view of the housing of the switch which also functions as a frame;

Fig. 8 is a perspective view showing the bridging contact members which perform their functions as will be shown;

Fig. 9 is a large perspective view of the portion of the switch actuator; and

Fig. 10 is a perspective view of one of the stationary contacts.

The switch comprises a frame 11, preferably molded from a suitable insulating material such as a rubber compound or a condensation product. This frame also acts as a housing and with a cover 12, the nature of which will be described more in detail as the description progresses, houses the entire switch apparatus. A generally cup-shaped recess 13 is provided and a center post 14 projects axially thereof and is integral with the frame or housing 11. A stem 16 is also formed

integral and is threaded to provide for mounting.

The switch includes a pair of stationary contacts 17 shaped as shown in Fig. 10 and secured in place by screws 18. The heads 17a of the stationary contact members rest in shallow wells provided in the frame at either side of the cup-shaped aperture therein. A slot forms a communication between these shallow well portions, and the cup portion and the stem portion 17b lie along and within this slot so as to hold the arcuate contact portions 17c in the lower part of the cup portion but against the side wall thereof.

The bridging contact member 19 is shown in Fig. 8. It is formed up of a single piece of phosphor bronze spring material and includes a pair of contacting blades 19a and a center ring structure 19b which acts as a pawl, as will be shown. This bridging contact member is seated down over the center post 14 and rests in the bottom of the cup-shaped opening with the contacting blades 19a in line with the portions 17c of the stationary contact members.

I also provide a member 21 (Fig. 9) for actuating the bridging contact member. For short, I term this member an actuator. It is cored to be threaded down over the center post 14 and its bottom portion is provided with a number of longitudinally projecting ratchet teeth 22 adapted to co-operate, in a manner to be described, with the upturned portion of the pawl member 19b of the bridging contact member. A coil spring 23 is disposed loosely within the actuator and around the post 14. One end thereof is turned inwardly and projects into a slot 14a running longitudinally of the center post and the other end is turned outwardly and engages in a recess 24 in the actuator. As will be noted clearly from Fig. 9, a lip 26 projects out over the recess 24 so as to extend over the projecting end of the spring 23 (see also Fig. 3).

For rotating the actuator, I provide a swivel ball type of chain 27 which extends through the hollow stem 16 around a portion of the actuator, as shown in Fig. 3, and engages in a slot or recess 28 formed longitudinally in the side wall of the actuator. Near this slot or recess 28, the outside surface of the actuator is finished with a series of grooves and ridges alternately arranged so as to permit the successive swivel balls of the chain 27 to have more friction and so avoid direct pull on the end ball of the chain which is held in the recess 28. In this manner, although the actuator is comparatively small and has a comparatively thin sidewall, ample strength is obtained

and the chain is readily fastened without the necessity of providing separate fastening means of any kind. To prevent the chain from dropping down and engaging the contact members, an annular flange 29 is provided extending over the entire portion of the actuator with which the chain comes in contact.

Projecting laterally from the actuator, I provide a stop 31 which engages a shoulder 32 formed outside the edge of the cup-shaped portion of the frame. Looking at Fig. 3, the movement of the actuator from the position there shown is in a clockwise direction. Accordingly, a portion of the frame is cut away to provide a ledge 33 and a corresponding open space sufficient to pass the stop 32. This makes it impossible to assemble the actuator in the frame or housing except in the position shown in Fig. 3, because at other portions around the periphery of the cup-shaped portion the stop 32 cannot be accommodated. At the opposite end of this open space, another shoulder is formed to limit the movement of the actuator in response to pulling the chain.

Below the ledge 33 on one side of the frame and throughout the length of the cup-shaped portion at the opposite side of the frame, four ratchet tooth-like recesses 34 provide a final shape as shown in Fig. 4. The result is a cam-like series of surfaces over which the blades of the bridging contact member move, whereby spring tension is built up in these blades as they rotate and they drop sharply off the shoulders provided between successive cam surfaces. This produces a quick making and breaking of contact, that is to say, a snap make and break action. These shoulders or steps between successive cam surfaces also have a ratchet action in that the blades of the bridging contact member function as pawls to prevent the bridging contact member as a whole from being rotated in a counter-clockwise direction when the actuator is returned by its spring.

The terminal wells in which the screws 18 are housed are connected by a pair of slots 36 running through the frame. These are to pass conductors which, as shown, are connected to the stationary contacts by means of the screws 18. The cover 12 is secured in place by an eyeflet type of rivet 37 which extends through the center post 14 and through the back of the housing or frame. This housing is provided with a small aperture 38 into which a teat 39 formed on the frame or housing portion projects. The cover, preferably formed of a material like a condensation product, has sufficient spring to release the teat 39 from the aperture 38 and permit the cover to be rotated to the position shown in Fig. 2. This exposes the conductor attaching screws 18 readily without exposing any other portion of the switch. The cover is slightly recessed at 41-41 to provide ample space for removing or loosening the screws when the cover is in the position of Fig. 2.

It will be noted that the switch is of exceedingly simple construction and has a very small number of parts. The housing or frame portion and the actuator are both arranged to be molded readily from suitable insulating material. The stationary contacts and the bridging contact member are readily formed by stamping operations.

In assembling the switch, the stationary contacts are dropped into position and secured with the screws 18. The bridging contact member is then grasped with a suitable jig to hold the spring

blades slightly compressed and dropped down into position at the bottom of the cup-shaped recess 13 and around the center post 14. The spring is then dropped into position in the actuator, with the downwardly projecting end engaging in the recess 24. The spring and actuator together are then threaded down over the center post with the inner projecting end of the spring engaging in the slot on the center post. Before the actuator is dropped down a sufficient distance to engage the bridging contact member, it is rotated partially until the stop 31 on the actuator is in line with the shoulder 32 formed on the frame or housing. At this position, it is forced in the remaining distance and will then occupy the position shown in Fig. 3. The pull chain is then dropped through the stem 16, pulled out a sufficient distance to circle the actuator, and the end ball of the chain inserted in the slot or recess 28 of the actuator. The chain is then pulled taut, after which the cover is applied in position and riveted snugly against the body.

In operating the switch, it is impossible for any kind of a short circuit to occur or for the chain to be caught in any way. Sometimes in switches of this character, if the chain is allowed to snap back, it will become lodged in against the contacts and cause a short circuit. Clearly this is impossible with the construction which I employ.

The manner in which the conductors are attached and the manner in which the switch functions during normal operation has been made clear in the body of the description.

I have described my invention in detail and have shown the co-operation between different features and parts thereof. It is obvious, however, that the invention is not to be restricted by the specific details shown but the scope thereof is defined by the appended claims.

What I claim as new and desire to protect by Letters Patent of the United States is:

1. In a switch, a housing bodily integrally formed of insulating material and having a generally cup-shaped opening therein, a pair of terminal wells in the housing spaced at the side of the opening, a pair of stationary contacts, each having a portion supported in the wells and each having another portion lying within a slot at the edge of the opening and lying along the lower side wall thereof, a bridging contact member disposed in the opening, means for partially rotating the bridging contact member to alternately bridge and disconnect said stationary contacts, conductor attaching means engaging the stationary terminals and disposed in the wells, and a cover for the housing opening pivotally supported on the housing and movable for rendering said conductor attaching means accessible without uncovering the bridging contact member or operating means therefor.

2. In a switch, a housing formed of insulating material and having a generally cup-shaped opening therein, a pair of terminal wells in the housing spaced at the side of the opening, a pair of stationary contacts, each having a portion supported in the wells and each having another portion lying within a slot at the edge of the opening and lying along the lower side wall thereof, a bridging contact member disposed in the opening, means for partially rotating the bridging contact member to alternately bridge and disconnect said stationary contacts, conductor attaching screws disposed in said wells and engaging the stationary contacts, and a cover pivotally secured to the housing at the center thereof and

normally covering said conductor attaching screws but adapted to be rotated to render said conductor attaching screws accessible without uncovering the remaining portions of the switch.

5 3. In a switch, a pair of stationary contacts spaced from each other, a bridging contact, an actuator for the bridging contact, a peripheral slot on the actuator parallel with the axis thereof, a plurality of peripheral corrugations adjacent the slot and parallel thereto, a swivel ball type pull chain having a terminal pawl disposed in the slot and successive balls engaging in said corrugations, the chain extending partially around the actuator, and a spring urging said actuator a direction opposite to the direction of rotation thereof in response to pulling of the chain.

20 4. In a switch, a housing body integrally formed of insulating material and having a generally cup-shaped opening therein, a center post integrally forming part of the body and disposed in the opening, a pair of stationary contacts carried at the side of the opening, a bridging contact member disposed at the bottom of the opening and surrounding the center post, an actuator journaled on the opening and having portions adapted to successively engage a portion of the bridging contact member, a spring having one end secured to the post and the opposite end secured to the actuator, and a pull chain secured to the actuator and partially extending around the same whereby to rotate the actuator and bridging contact member against the action of said spring.

25 5. In a switch, a housing formed of insulating material and having a generally cup-shaped opening therein, a center post formed of insulating material and having a longitudinally extending peripheral slot therein, stationary contacts at the side of the opening, a bridging contact member journaled around the post, an actuator extending around the post but spaced therefrom, a coil spring disposed between the post and actuator and having one end engaged in a slot in the actuator and the opposite end engaged in said slot in the post, a plurality of equally spaced projections on the actuator adapted to successively engage a portion of the bridging contact member, and a pull chain engaging the actuator to rotate the same against the tension of said spring, said portion of the bridging contact member functioning as a spring pawl to permit return movement of the actuator by the spring without moving the bridging contact member.

30 6. In a switch, a housing body integrally formed of insulating material with a generally cup-shaped opening therein, a plurality of cam surfaces on the side walls of the opening interconnected by shoulders, all of which face in the same direction, stationary contacts lying along oppositely facing cam surfaces, a bridging contact member centrally disposed in the opening and having a pair of spring blades engaging opposite cam surfaces, an upwardly extending spring projection integral with the bridging contact member, an actuator disposed in the opening and having a plurality of ratchet teeth adapted to successively engage the spring projection of the bridging contact member, and means for reciprocating the actuator through a radius equal to the length of the ratchet tooth and cam surfaces, rotation of the actuator in one direction serving to rotate the bridging contact member, while on rotation in the opposite direction a bridging contact

member is disengaged and the blades thereof serve as pawls by engaging against the shoulders of the cam surfaces.

7. In a switch, a housing formed of insulating material and having a generally cup-shaped opening therein, a center post projecting from the housing into the opening, a pair of terminal wells formed in the housing at the sides of the opening, stationary contacts having portions secured in the wells and other portions extending along slots in the housing at the side of the opening with portions lying along the inside wall of the opening, an integral bridging contact member extending around the post with the blades adapted to engage stationary contacts to bridge the same, and an upwardly extending spring-like projection, an actuator journaled on the post but spaced therefrom, a spring having one end engaging in a slot in the post and another end engaging in a slot in the actuator, a pull chain having an end ball engaging in a slot in the actuator and partly extending around the actuator, and ratchet like teeth carried by the actuator and adapted to successively engage the spring like projection on the bridging contact member when the actuator is rotated.

20 8. In a switch, a housing formed of insulating material and having a generally cup-shaped opening therein, a center post projecting from the housing into the opening, a pair of terminal wells formed in the housing at the sides of the opening, stationary contacts having portions secured in the wells and other portions extending along slots in the housing at the side of the opening with portions lying along the inside wall of the opening, an integral bridging contact member extending around the post with the blades adapted to engage stationary contacts to bridge the same, and an upwardly extending spring-like projection, an actuator journaled on the post but spaced therefrom, a spring having one end engaging in a slot in the post and another end engaging in a slot in the actuator, a pull chain having an end ball engaging in a slot in the actuator and partly extending around the actuator, ratchet like teeth carried by the actuator and adapted to successively engage the spring-like projection on the bridging contact member when the actuator is rotated, an outward projection on the actuator, and shoulders on the housing for engaging the projection to limit the movement of the actuator in both directions, said projection engageable only between said shoulders whereby the actuator can be assembled in the housing only with a predetermined tension on the spring.

35 9. In a switch, a housing formed of insulating material and having a generally cup-shaped opening therein, a center post projecting from the housing into the opening, a pair of terminal wells formed in the housing at the sides of the opening, stationary contacts having portions secured in the wells and other portions extending along slots in the housing at the side of the opening with portions lying along the inside wall of the opening, an integral bridging contact member extending around the post with the blades adapted to engage stationary contacts to bridge the same, and an upwardly extending spring-like projection, an actuator journaled on the post but spaced therefrom, a spring having one end engaging in a slot in the post and another end engaging in a slot in the actuator, a pull chain having an end pawl engaging in a slot in the actuator and partly extending around the actuator, ratchet like

- teeth carried by the actuator and adapted to successively engage the spring like projection on the bridging contact member when the actuator is rotated, a pair of channels formed in the housing and running to the terminal wells, conductor attaching means in the wells engaging the stationary contacts, a relatively thin walled cover for the housing extending over the actuator, terminal wells and said channels, a single fastening means extending through the housing, through said center post and cover, whereby to rotatably secure the cover to the housing, and releasable engaging means between the cover and housing whereby said cover may be rotated to expose said terminal wells and channels without uncovering the remaining portion of the switch mechanism.
10. In a switch, a housing, switch mechanism in the housing, a terminal screw carried by the

housing, a cover for the housing normally covering said terminal screw and switch mechanism, and a single swivel connection through a central portion of said cover, whereby said cover may be rotated to expose said screw without exposing said switch mechanism.

11. In a switch, a housing having a cup-shaped opening therein, switch mechanism mounted in the opening, a pair of terminal screws in the housing diametrically oppositely disposed relative to the switch mechanism in the opening, a flat cover of insulation material for the housing and covering said switch mechanism and terminal screws, said cover plate being centrally pivoted and rotatable to expose the terminal screws without exposing the switch mechanism.

RUDOLF POPP.
